IMPULSE SWITCHING AND CONTROL
MECHANISMPaul E. Fischler and John Nathansohn,
Buffalo, N. Y.

Application July 21, 1942, Serial No. 451,804

2 Claims. (Cl. 177—353)

Our present invention relates to an improved impulse switching and control mechanism adapted for use particularly in remote control operation for various devices.

According to the present disclosure, the invention is especially adapted for use with torpedoes operated and controlled from a remote station. The remote station may, of course, be located either on the land, in the air, or on a vessel.

Obviously the control mechanism and circuits hereinafter described more specifically may well be employed in any device where remote control is suitable or desirable.

The invention consists generally in a radio impulse transmitter from which the impulse is received by the remote object, which in our embodiment is, a torpedo. The receiving object contains a super-regenerative detector tube, from which emanates the audio impulses. These audio or A. C. impulses are then amplified. The amplified A. C. current impulses may be rectified into D. C. currents if desired, and in the present embodiment we prefer such impulses.

These D. C. impulses actuate a series of relays with their independent current source, and the relays in turn motivate means for operating a multiple contact switch. From this switch through the various circuits, the motor of the torpedo is controlled, and the vertical and horizontal rudders or fins may be shifted as may be necessary to direct the torpedo toward its objective.

In the accompanying drawing we have illustrated one complete embodiment of the physical construction of our invention according to the best mode we have thus far devised, but it will be understood that changes and alterations may be made in the exemplified structure within the scope of the appended claims.

The single figure is a diagrammatic view showing the electric circuits, relays, and associated elements comprising the control circuit.

Reference is now had to the single figure of the drawing. This figure shows the circuits comprising the invention, it being understood that the sending and receiving circuits to be used therewith are substantially conventional.

In the selector and control circuits we employ a ratchet wheel 18 having fixed thereon a switch arm 19. The ratchet wheel is rotated by means of a pawl 20, one step for each impulse received. The pawl 20 is attracted by energization of relay 21, the circuit for which is closed upon operation of contact 22 under control of the relay 17 receiving the D. C. impulse.

Simultaneously with the actuation of relay 21, contact 22' of relay 17 operates relay 23 which opens contact 24 and the first movement of the pawl 20 closes contact 25. One-quarter second after impulses stop, relay 23 returns to normal, closing contact 24, thereby completing circuit through contact 25, actuating relay 26 to rock pawl 27 and release the wheel, which returns to neutral position and again opens contact 25.

10 Battery 28 supplies current for these relays and the relays 31, 41, 51, 61, 71, and "H" respectively.

15 The switch arm 19 is adapted to rotate with the wheel and to contact successively contacts 30, 40, 50, 60, and 70. These contacts are electrically connected respectively with relays 31, 41, 51, 61, and 71, (only five relays necessary for torpedo control). These relays are successively energized as the switch arm 19 moves over the contacts 30, 40, 50, 60 and 70. As the ratchet

20 wheel 18 is revolved in a clockwise direction, a circuit is momentarily closed from the battery 28 through pawl 27, ratchet wheel 18, switch arm 19, and one of the contacts 30, 40, 50, 60 or 70, to the relay 31, 41, 51, 61 or 71 associated therewith.

25 The control contacts of relays 41, 51, 61, and 71 are shown in the circuit and selectively control the motor relay "H," or the motor relay "H" and one of the solenoids 91, 92, or 93.

30 The motor "M" with its power circuit and battery 94 is the driving means for the torpedo. Solenoids 91 and 92 in this circuit are geared to the vertical rudders and when energized, solenoid 91 moves the rudders to the right, and solenoid 92 moves the rudders to the left. Solenoid 93 in the said circuit is geared to the horizontal rudders and when energized actuates the horizontal rudders.

35 When the relay 17 is energized by an impulse, the contacts 22 and 22' are attracted to the relay and their respective circuits are closed. Contact 22 closes the circuit from the battery 28 to energize the relay 21. Contact 22' energizes relay 23.

40 Relay 23, when energized, opens the contact 24 and this relay is so constructed as to operate on the first impulse and to continue to hold so long as impulses continue and for one-quarter second thereafter.

45 Immediately upon cessation of impulses, following the one-quarter second delay, relay 23 releases and closes contact 24 for purposes as will be hereinafter set forth. The transmitted impulse time is at the rate of ten per second and relays 41, 51, 61, and 71 are designed for a one-fifth second delay on pull in.

Energization of relay 21 attracts an arm mechanically connected to pawl 20. This pawl is operable upon the ratchet wheel 18 to rotate the same, and every impulse imparted to the relay 21 will impart one clockwise step to the ratchet wheel.

For clarity of explanation, a single circuit will now be described, it being understood that relay 31 is energized by passage of switch arm 19 over contact 30, this instantly opens contact 32, and breaks the holding circuits to relays 41, 51, 61, and 71 and instantly releases any one of these relays which has been locked-in by a previous operation. Contact 33' keeps the holding circuit to relay 41 closed, unless switch arm 19 pauses on contact 50, and relay 51 pulls in. The same function is performed by contacts 43' and 53' in connection with relays 51 and 61 respectively.

From the above it will be clear that the first impulse of a series causes relay 31 to open contact 32 and release any one of the relays 41, 51, 61 and 71 which have been locked in by a previous series of impulses, two impulses control circuit to motor relay "H," three impulses close another control circuit to solenoid 91 and motor relay "H" and so on. The last impulse of the series allows the arm 19 to pause on the selected contact 40, 50, 60 or 70 for $\frac{1}{4}$ second until the delayed release of relay 23 closes the contact 24, completing a circuit from the battery 28 through contact 25 to relay 26, which, when energized, releases pawl 27 and allows ratchet wheel 18 to return to neutral position.

With a one impulse signal transmitted and received, the spring returned ratchet wheel 18 rotated one step. This moves the contact arm 19 to the first connector 30. With the switch arm 19 on connector 30 the circuit is closed to relay 31. Relay 31 attracts contact 32 and opens the circuit from the battery 28. By thus opening the contact 32 and breaking the holding circuit through contacts 33-33', 43-43', 53-53' and 63, any one of the relays held in by a previous operation is released and the circuit cleared for the following sequence. It will be perceived that relay 31 operates upon the initial impulse of any sequence and immediately releases to close the circuit through that point.

Proceeding now with the illustrative circuit, relay 21 operates actuating pawl 20. This movement closes contact 25 preparatory to energizing relay 26 to release pawl 27.

Upon receipt of the second impulse, the energization of relays 21 and 23 is repeated and the arm 19 now contacts contact 40. The circuit is then closed to relay 41 and the holding contact 33 is closed, simultaneously closing contact 34 in the motor relay "H" circuit.

Through the closing of the main or live wire 95, the circuit is completed to battery 94 which operates the motor "M" to drive the torpedo. It will be apparent, it is believed, that any number of impulses from 2 to 5 transmitted will continue to operate the motor through contacts 34, 44, 54, or 64.

When the contact arm is, upon receipt of a higher sequence of impulses, moved to 50, 60, or 70, the solenoids 91, 92, or 93 are actuated through their respective circuits and contacts 45, 55, 65, and the horizontal or vertical rudders are changed as desired, relay "H" through contacts 34, 44, 54, or 64 holding motor circuit closed.

Relays 41, 51, 61, and 71 are designed for one-fifth second delay on contact actuation. Motor 75

relay "H" is designed for one-quarter second delay on release, and with relay 23 holds for one-quarter second after the last impulse has been received and passed. The control relay associated with the connector on which the switch arm 19 stops pulls in during the time delay between the last impulse and release of relay 23, and the control relay is then locked in by contacts 33-33', 43-43', 53-53', or 63. Likewise, relay 10 "H" holds in during the travel of switch arm 19 from connector 40 to connector 50, 60, or 70.

Resetting of the device is automatically accomplished by the contact 24 of relay 23, closing the circuit to relay 26, through contact 25 one-quarter second after the last impulse, thus releasing pawl 27 and allowing the switch arm 19 to release and return to neutral position. Simultaneously, the circuit from battery 28 to switch arm 19 is opened by pawl 27, preventing energization of non-selected control relays as arm 19 returns to neutral position.

Opening energizing circuit to switch arm or wiper 19 as it returns to neutral position also prevents operation of relay 31. It must be borne in mind that relay 31 is fast acting while control relays 41, 51, 61 and 71 are designed for one fifth of a second delay on pull-in. If energizing circuit to switch arm 19 remains closed as it returns to neutral, the control relays would not normally operate because of their delayed action, but relay 31 would be actuated and the control function set up would be released through opening of contacts 32. For this reason it is necessary to open the energizing circuit to switch arm 19 as it returns to neutral position.

It will be seen that the system provides a method of releasing a control function immediately before establishing a new function as operation of relay 31, on the first impulse of any group of impulses, opens control relay 41, 51, 61 or 71 holding circuit through contact 32. It should be understood that this method eliminates the necessity of transmitting a separate release signal and consequently a control function can be released and a new one set up in a fraction of a second. In applications involving the control of fast moving objects, for instance, a torpedo, such a method is absolutely essential.

Pawl 27 of release magnet 26 opens the connection from 28 to arm 19, thereby preventing the energizing of clearing relay 31 as arm 19 returns to neutral position. This function is necessary to prevent contacts 32 of relay 31 from opening locking circuits to selected control relay 41, 51, 61 or 71. In this manner a series of impulses selects a desired control relay which remains locked in until a second series of impulses is transmitted. The purpose of having a succeeding relay of group 41, 51, 61 and 71 open the locking circuit of its preceding relay is to provide double assurance that only the selected control relay will be locked in.

Through the utilization of our invention a simple remote control may be accomplished without the usual disadvantages of delicately adjusted parts, and a rugged, dependable control system is presented. Mechanical or electrical re-cycling or resetting of the device is eliminated by the automatic resetting operation, and the utilization of relay 31 obviates the necessity of the usual timing relay or motor.

Having thus fully described our invention, what we claim as new and desire to secure by Letters Patent is:

1. A selective system responsive to different

series of impulses of different number in each series, comprising a plurality of slow to operate relays, a fast operating relay, each of said slow to operate relays having means for closing a locking circuit for its relay when it is operated and the fast operating relay having means for opening the locking circuits of the slow to operate relays when the fast operating relay is operated, a movable switch arm and cooperating contacts, a circuit connection from one of said contacts to the fast operating relay whereby it will operate when the movable switch arm moves over said one contact, circuit connections from succeeding contacts to respective said slow to operate relays, means responsive to individual impulses of a series for moving said movable arm for each impulse a step over said contacts to thereby operate said fast to operate relay in response to any series of impulses and operate one of said slow to operate relays corresponding to the contact engaged by the movable arm at the end of the series of impulses, means operative a predetermined period after the termination of the series of impulses to return said arm over the contacts to normal position and means operative during the return movement to render fast operating relay inoperative when the arm engages the contact corresponding to the fast operating relay upon its return movement.

2. A selective system responsive to different

series of impulses of different number in each series, comprising a fast operating relay, a plurality of slow to operate relays, each of said slow to operate relays having means for closing a locking circuit for its coil circuit when it is operated and the fast operating relay having means for opening the locking circuits of the slow to operate relays when the fast operating relay is operated, a movable switch arm and cooperating contacts, a circuits connection from one of said contacts to the fast operating relay whereby it will operate when the movable switch arm passes over said one contact, circuit connections from succeeding contacts to respective said slow to operate relays, means responsive to individual impulses of a series for moving said movable switch arm for each impulse a step over said contacts to thereby operate said fast to operate relay in response to the first impulse of any series of impulses and to operate the slow to operate relay connected to the contact engaged at the last impulse of any series of impulses, means operative a predetermined period after the termination of the series of impulses to return said switch arm over the contacts to normal position and means operative during the return movement to render all relays inoperative.
